JESSE TEMPLE CURTIS, OF BEMENT, ILLINOIS, ASSIGNOR OF ONE-HALF TO F. LYNN
McCLURE, OF SEBRING, OHIO.

ENGINE-VALVE.

1,273,585.

Specification of Letters Patent. Patented July 23, 1918.

Application filed October 16, 1917. Serial No. 196,889.

To all whom it may concern:

Be it known that I, JESSE T. CURTIS, a citizen of the United States, residing at Bement, in the county of Piatt and State of Illinois, have invented a new and useful Engine-Valve, of which the following is a specification.

The present invention appertains to valves for internal explosion engines, and aims to provide a novel and improved valve structure to enhance the operation, especially in high speeds, which are ordinarily handicapped by the present types of valves.

The invention has for its object the provision of a novel valve structure wherein the intake and exhaust valves coöperate in an effective manner, in connection with novel means for operating valves.

A further object of the invention is to avoid the objections to ordinary puppet exhaust valves, which frequently warp, and burn and pit at their seats.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Fig. 1 is a section of an engine equipped with the valve construction, portions being shown in elevation.

Fig. 2 is a section on the line 2—2 of Fig. 1.

In the drawing, there is illustrated an internal explosion engine having one cylinder, but it will be readily appreciated that the valve structure can be duplicated for multiple cylinder engines, the operation of each valve structure being the same and in timed relation with the corresponding piston. Within the cylinder 1, the piston 2 reciprocates as usual, being connected by the connecting rod 3 with the crank shaft 4, which works in the crank casing 5. The head of the cylinder can be integral or removable.

In carrying out the invention, the casting of the cylinder is formed at one side with a longitudinal cylindrical valve casing 6, and

the partition between the cylinder and valve casing is provided with a port 8 at the head of the cylinder and establishing communication between the head end of the cylinder and the outer end of the valve casing. The 60 valve casing 6 is provided near its inner end with an intake port 9, and between its ends with an exhaust port 10, to communicate with the intake and exhaust manifolds, respectively.

A piston or sleeve valve 11 to control the exhaust is slidable within the valve casing 6, having a longitudinal bore or passage extending therethrough from end to end, and the outer end of the sleeve valve 11 has a 70 seat 12 for a puppet valve 13 to control the intake of fuel seatable away from the port 8 against said seat to close the opening at the outer end of the sleeve valve 11. The sleeve valve is provided near its inner end 75 with an inclined or oblique partition 14 and a port 16 in one side at the lower end of said partition to register with the port 9. The partition has a depending tubular guide 15 through which the stem 13' of the valve 80 13 extends downwardly from within the valve 11. To operate the valve 11 it is connected by a connecting rod 17 with an auxiliary valve crank shaft 20 mounted for rotation within the crank casing. A gear 85 wheel 21 secured to the crank shaft 20 meshes with a gear wheel 22 of one-half less size secured to the crank shaft 4, whereby the valve crank shaft 20 is rotated once for two revolutions of the crank shaft 4 although any other suitable connection between the shafts can be used to obtain this ratio of rotation, as usual in a four-cycle engine. The connecting rod 17 has a forked or bifurcated portion 18 at one end having its 90 95 arms pivoted, as at 18', to the valve 11 within its lower end and at opposite sides of the guide 15 to provide a compact structure, while the other end of the connecting rod has a fork 19 journaled on the crank 20. 100 The puppet valve 13 is unseated by a push rod 23 extending slidably through the tubular connecting rod 17 with one end of the rod 23 bearing against a shoe 27 secured to the end of the valve stem 13'. The rod has 105 a shoe 24 to bear on the shaft 20. A coiled wire expansion spring 25 or other suitable spring is used for holding the valve 13 to its seat, said spring, as illustrated, surrounding the guide 15 and being confined between 110

and bearing against the shoe 27 and a shoulder 26 of the guide. The unseating of the valve 13 is accomplished by a cam 28 carried by the crank of the crank shaft 20 which engages the shoe 24. The fork 18 accommodates the bearing 15, spring 25, and shoe 27 while the fork 19 accommodates the shoe 24 and cam 28. The cam 28 is so arranged, that during the intake stroke of the 10 piston 2, the cam 28 moves under the shoe 24 to lift the rod 23 and stem 13' and unseat the valve 13, as will be explained presently.

In operation, starting with the position of the parts as illustrated, when the piston 15 2 moves through its intake stroke away from the head, the crank of shaft 20 moving through the arc marked, "Intake," raises the connecting rod 17 and valve 11 covering the port 10 and bringing the port 20 16 into register with the intake port 9. The turning of the crank shaft 20 will move the cam 28 under the shoe 24, thus lifting the stem 13' and valve 13, and permitting the carbureted air to be sucked into the cylinder 25 by the motion of the piston 2, through the ports 9 and 16, sleeve valve 11, and port 8. When the piston 2 reaches the end of the intake stroke, the crank of shaft 20 in being moved near its uppermost position, will 30 move the cam 28 from under the shoe 24 so that the valve 13 will be seated by the spring 25. When the piston 2 moves outwardly through the compression stroke, the crank shaft 20 is moving over the axis of 35 said shaft through the angle marked "Compression," the valve 11 thus being in its uppermost position and closing the exhaust port 10, while the valve 13 in closing the port of the valve 11 prevents the escape of 40 compression. Then, after the piston 2 has reached the end of its compression stroke, and moves through its explosion stroke, the compressed gas being ignited by a spark plug or other suitable igniter, the crank of 45 the shaft 20 moves through the arc marked "Explosion," thereby pulling the connecting rod 17 and valve 11 downwardly, the valve 13 remaining seated on the seat, 12 since the turning of the crank shaft 20 to-

ward the left will serve to swing the cam 28 away from the shoe 24. When the piston 2 reaches the end of the explosion stroke and returns during its exhaust stroke, the crank of shaft 20 moves under the axis of said shaft through the arc marked "Exhaust," whereby the upper end of the valve 11 and valve 13 will be below the upper portion of the exhaust port 10, thereby permitting the exhaust gas to escape, but the valve 13 remains seated to prevent the exhaust 60 from reaching the intake port. The above operation is then repeated.

With this construction, the exhaust valve 11 is reciprocated once for every two reciprocations of the piston 2, the valve 13 moving with the exhaust valve 11, and being opened at the proper time. This operation of the valves enables the engine to attain a high speed without being handicapped by the sluggish movement of the valves.

Having thus described the invention, what is claimed as new is:

An engine valve structure embodying a casing to communicate at one end with a cylinder and having intake and exhaust ports, one near its other end and the other between its ends, a sleeve valve slideable within the casing to control the second mentioned valve to communicate with the other port and having a valve seat near the first mentioned end of the casing, a puppet valve seatable against said seat and having a spring-pressed stem slideable through the sleeve valve, a crank, a connecting rod connecting said crank and sleeve valve, a push rod slideable in the connecting rod to move said stem, and a cam carried by the crank and engageable with said push rod to unseat the puppet valve during one movement of the sleeve valve.

In testimony that I claim the foregoing as my own, I have hereto affixed my signature in the presence of two witnesses.

JESSE TEMPLE CURTIS.
